UNITED STATES PATENT OFFICE.

HENRY A. ALLWARDT, OF DETROIT, MICHIGAN.

SODA-WATER APPARATUS.

SPECIFICATION forming part of Letters Patent No. 680,011, dated August 6, 1901.

Application filed February 8, 1901. Serial No. 46,494. (No model.)

To all whom it may concern:

Be it known that I, HENRY A. ALLWARDT, a citizen of the United States, residing at Detroit, county of Wayne, State of Michigan, 5 have invented a certain new and useful Improvement in Soda-Water Apparatus; and I declare the following to be a full, clear, and exact description of the invention, such as will enable others skilled in the art to which 10 it pertains to make and use the same, reference being had to the accompanying drawings, which form a part of this specification.

My invention relates to soda-water apparatus; and the object of my improvements is 15 to provide an approved apparatus for refilling tanks with carbonated water which shall be simple in construction, well adapted to be used with usual apparatus for this purpose, and which shall utilize the residual gases in 20 the exhausted tanks. I accomplish this object in the device illustrated in the accompanying drawings, in which—

Figure 1 is an elevation of a carbonating apparatus embodying my invention, the chamber in which the water is mainly charged with 25 gas being shown in section. Figs. 2 and 3 are sections taken at right angles to each other through the center of the tank. Fig. 4 is a section of the pressure-regulating valve. 30 Fig. 5 is an enlarged sectional view of the automatic stop-valve, and Fig. 6 is a plan view in section of the valve and valve-seat shown in Fig. 5.

The same letter indicates the same part in 35 each of the views.

A is a force-pump.

B is a carbonating-chamber.

C is a pipe which connects the chamber A with a source of supply of carbonic-acid gas 40 under pressure.

D is a pipe by which the carbonated water may be allowed to flow from the chamber A. The gas is admitted through the pipe C and by suitable apparatus is kept at a certain pressure—say one hundred and eighty pounds—in the chamber B. The water is forced by 45 the pump A into the top of the chamber B, where it is sprayed through a perforated plate to expose it to the gas, which it absorbs, and it gathers at the bottom of the chamber, 50 so as to cover the mouth of the outlet-pipe D.

E E' are tanks in which the carbonated water is supplied to retail dealers. These tanks are of the same construction and are only distinguished in the reference-letters to 55 indicate their relative positions, as shown in Fig. 1. Through an aperture in the top of the tank E is fixed a plug F, which extends to near the bottom of the tank.

G is a nozzle extending laterally from the 60 plug F outside of said tank.

g is a passage extending through the nozzle G and opening into a chamber H in the plug F.

f is a passage opening into the tank E at 65 the lower end of the plug F, extending to the top of said plug and communicating at its upper end with the chamber H.

h is a valve adapted to close the entrance 70 from the chamber H to the passage f.

I is a second passage in the plug F, extending from a point about quarter of the length of said plug from the top thereof, where it opens into the tank, to the upper end of said plug, at which point it passes through a nozzle J.

K is a chamber formed in the upper end of the plug F, forming an enlargement of the passage I.

k is a ball in the chamber K. This ball is 80 prevented from closing the lower passage to the chamber K by ribs i i, Figs. 5 and 6, but is adapted to close the upper passage to said chamber when it is raised sufficiently.

The pipe D, through which the carbonated 85 water from the chamber B passes, is connected to the nozzle G. A pipe L is connected to the nozzle J and leads to a reducing-valve M, which is adapted to open to permit the passage of a fluid from the pipe L whenever 90 the pressure in said pipe is greater than a certain amount less than the pressure in the chamber B—say one hundred and sixty pounds. N is a pipe leading from the outlet-passage of the valve M to the inlet-nozzle G' 95 of a second plug F' of the same construction as the plug F.

n is a pressure-gage on the pipe N. Other plugs, like F F', with their connected tanks, may be connected in the same way, except 100 that only one valve similar to M or gage similar to n will be required.

R is a pipe connecting the pipe C with the pipe L. r is a stop-cock on the pipe R.

S is a stop-cock on the pipe D.

s' is a stop-cock on the pipe N.

5 The operation of the above-described apparatus is as follows: The tanks come in to be refilled with the plugs F in them, the valves h closed, the water withdrawn, but still filled with carbonic-acid gas at a small pressure. One tank is connected, as above described, to the pipe D, and one or more other tanks E' are connected with the first, as above described. The cock r is opened, allowing the gas to flow into the tank E until 15 the pressure therein is equal to that at which the valve M is set. The cock in the pipe D is then opened, allowing the carbonated water to flow into the tank E through the passage f. As the water rises in said tank it 20 presses the gas in the tank before it and absorbs a part of it. When the pressure of the gas in the tank E exceeds one hundred and sixty pounds or the pressure to which the valve M is set, said valve opens, allowing the 25 gas to pass by it and into the tank E'. When the level of the water in the tank E rises above the lower opening of the passage I, the water rises in said passage, carrying the ball k upward and closing the passage I by stopping the upper passage from the chamber K, whereupon the pressure in the tank rises to that of the chamber B and the water ceases 30 to flow. The valve h and cocks S are now closed, the tank E removed from the pipe D, 35 the tank E' put in its place, and a third tank put in the place of the tank E', and the operation is repeated.

It may be noticed that in the above-described apparatus the tank is always filled to the same extent—that is, to a level just above 40 the lower end of the passage I—that all the residual gas of the tanks is utilized, that the water will always be carbonated to about the same extent, and that very little additional 45 apparatus is required. Of course the cock s' is closed before removing the tank E'.

What I claim is—

1. The combination with a tank E, having a passage-way opening toward its bottom, means for detachably connecting said tank 50 with a source of supply of carbonated water under pressure so that said water may enter said tank through said passage, said tank being also provided with a passage I opening into said tank near the top thereof, of a pipe 55 L adapted to be detachably connected to said tank so as to form a continuation of the passage I, a pressure-regulating valve on the pipe L adapted to open when the pressure in said pipe is a little less than the pressure forcing 60 the water into the tank E, and a second tank E' detachably connected to the outlet-passage of said reducing-valve and adapted to replace the first-mentioned tank, substantially as described. 65

2. The combination with a tank E having a passage-way opening toward its bottom, means for detachably connecting said tank with a source of supply of carbonated water under pressure, so that said water may enter 70 said tank through said passage, said tank being also provided with a passage I opening into said tank near the top thereof and provided with apparatus adapted to permit the passage of a gas, but to close the passage 75 when the water flows therethrough, of a pipe L adapted to be detachably connected to said tank so as to form a continuation of the passage I, a pressure-regulating valve on the pipe L adapted to open when the pressure in 80 said pipe is a little less than the pressure forcing the water into the tank E, and a second tank E' detachably connected to the outlet-passage of said reducing-valve and adapted to replace the first-mentioned tank, substantially as described. 85

In testimony whereof I sign this specification in the presence of two witnesses.

HENRY A. ALLWARDT.
